UNITED STATES PATENT OFFICE.

HENRY W. BODENDIECK, OF ST. LOUIS, MISSOURI.

AUTOMATIC CAR-FENDER.

No. 888,578.

Specification of Letters Patent.

Patented May 26, 1908.

Application filed August 30, 1907. Serial No. 390,781.

To all whom it may concern:

Be it known that I, HENRY W. BODENDIECK, a citizen of the United States, and resident of St. Louis, Missouri, have invented 5 certain new and useful Improvements in Automatic Car-Fenders, of which the following is a specification.

This invention relates to improvements in automatic car fenders and consists in the 10 novel arrangement, construction and combination of parts as will be fully hereinafter described and claimed.

The object of my invention is to construct a car fender to be operated automatically 15 whenever an object comes in contact with the front grill or vertical section of the fender.

A further object of my invention is to arrange in combination with an ordinary front fender of a car a horizontal fender which will 20 automatically contact with the track and be advanced forwardly underneath the front fender whenever an object comes in contact therewith.

In the drawings: Figure 1 is a side elevation 25 of my complete invention showing the same in its normal or raised position. Fig. 2 is a top plan view of the same removed from the car body.

In the construction of my invention I provide 30 a pair of supports 3 which are rigidly attached at the top to the under side of the car body or platform 4 of the car. In the supports and near the bottom are formed elongated openings or slots 5, and in said slots 35 operate sheaves 6, one located on each end of the operating shaft 7, the said shaft 7 being connected centrally to a connecting rod 8 by which the shaft 7 is operated forwardly or rearwardly by means of the manipulation of 40 the fulcrum 9. The fulcrum 9 is pivotally connected to the brace 10, which is supported to the under side of the car, the short end of said fulcrum being pivotally connected to the piston rod 11 of the air cylinder 12.

To the shaft 7 is hingedly attached a horizontal fender 13, the said fender being formed 45 of a plurality of strips 14 made preferably of spring material and suitably bent as shown in Fig. 1 so as to retain the body or object 50 whenever the same contacts therewith.

The strips 14 are supported to the cross strips 15, the innermost strip 15 being secured to the hinges 16 by which the said fender is retained in position upon the shaft 7.

The outermost ends of the strips are suitably bent forming the rounded ends 17 so as

to permit the strips to pass over cobblestones or the like in the track and preventing the same from puckering and being bent out of shape.

To the under side of the car and on each side of the cylinder 13 is suspended a pair of hangers 18. To the lower end of each is pivoted a link 19. To the free end of each link is connected a rod 20, the said rod extending 65 underneath the entire fender and arranged to support said fender in a raised position as shown in Fig. 1 when the same is not in use. Upon said rod is attached a lever 21 which is arranged at an angle opposite to the links 19 70 and to the end of said lever is connected a rod 22, its opposite end being connected to the end of the horizontal bar 23. The opposite end of the horizontal bar 23 is bent upwardly forming the projection 24, which 75 comes in contact with the shaft 7 to retain the rod 20 in raised position, and thus support the fender.

The air cylinder 12 is located under the platform at any suitable position and is arranged with suitable pipe connections 25 by which air is admitted into the cylinder from the proper air supply. In order to automatically place the fender in operation when the same contacts with an object I provide 80 a valve 26, the valve stem being connected to a rod 27 and the said rod projecting forwardly and being connected to the inner surface of the grill or vertical section of the fender 28. This section is of an ordinary 85 type of fender made of strips and supported to the dashboard of the car at the point indicated by the numeral 29 and is of sufficient resiliency as to permit the same to bend inwardly when an object contacts therewith, operating the rod 27, opening the valve and permitting the air to pass into the air cylinder 12. Immediately upon the admission of air into the cylinder the piston 11 is operated, which places in operation the fulcrum 9 and 90 instantaneously the shaft 7 together with the fender 13 is thrust forwardly and while the shaft 7 is leaving the projection 24 and the bar 22, the weight of the cylinder, by means of its forward movement, will have the tendency to overbalance the rod 20, permitting the fender to fall upon the track and advance forwardly underneath the front section 28 to receive the object with which the car may come in contact.

When the fender has been operated and it is desired to replace the same in its normal

position, the motorman by the operation of the valve 30 can force the air in the opposite end of the cylinder, which will replace the operating mechanism in reverse action drawing the fender 13 rearwardly as the shaft 7 comes in contact with the projection 24 of the bar 23 it will pull upon the same and cause the rod 20 to contact with the under surface of the fender and again raise the 10 same to its normal position as shown in Fig. 1.

The fender can be operated by the motorman as well as by the automatic connection, but the most essential feature of my invention is the thrusting forwardly of a section 15 of the fender permitting the same to contact with the track and preventing the object from passing beneath the front fender and contacting with the wheels of the car. 20 The forward movement of the fender is such as to permit the same to pass outwardly underneath the front section of the fender a suitable distance to catch and support the object.

25 Having fully described my invention, what I claim is:

1. A device of the class described comprising a fender section hingedly mounted upon a shaft; means for supporting the shaft

upon the under side of the car; a lever mechanism connected to said shaft and operated by an air cylinder in combination with a front fender section having connection with the air cylinder whereby the lower fender section may be automatically advanced forwardly when the front fender section is brought in contact with an object, substantially as specified. 30 35

2. A device of the class described comprising a fender section located beneath the car body; a pair of supports suspended from the car body; a shaft located in the supports and operating in slots formed in the supports; an air cylinder; a lever mechanism operated by the air cylinder and connected to the fender section in combination with a front fender section and means for admitting air into the air cylinder for operating the fender section when the front fender section is brought in contact with an object, substantially as 40 45 50 specified.

In testimony whereof, I have signed my name to this specification, in presence of two subscribing witnesses.

HENRY W. BODENDIECK.
